UNITED STATES PATENT OFFICE.

JACOB R. SANDAGE, OF OREGON, ILLINOIS, ASSIGNOR OF ONE-HALF TO CHARLES W. WATSON, OF CHICAGO, ILLINOIS.

HOT-AIR ENGINE.

1,083,946.

Specification of Letters Patent.

Patented Jan. 13, 1914.

Application filed March 25, 1912. Serial No. 686,109.

To all whom it may concern:

Be it known that I, JACOB R. SANDAGE, a citizen of the United States, and a resident of Oregon, in the county of Ogle and State 5 of Illinois, have invented certain new and useful Improvements in Hot-Air Engines; and I do hereby declare that the following is a full, clear, and exact description thereof, reference being had to the accompanying 10 drawings, and to the letters of reference marked thereon, which form a part of this specification.

This invention relates to hot air or caloric engines and has for one of its objects to provide an engine of this type which is simple 15 in construction and effective in operation.

The invention consists of the matters hereinafter described and more particularly pointed out in the appended claims.

20 In the accompanying drawings illustrating my invention: Figure 1 is a view representing a side elevation of a hot air engine constructed in accordance with my invention; Fig. 2 is a view representing a section 25 in a plane indicated by the line 2—2 of Fig. 1; Fig. 3 is a view representing a section on an enlarged scale in a plane indicated by the line 3—3 of Fig. 1.

Referring to the drawings, A indicates a 30 base or table-like stand for the engine as a whole, having a flat horizontal top *a* provided with a centrally disposed opening through which extends and in which is rigidly secured an upright tubular casing B, 35 which is preferably cylindric in form and made of sheet metal, and supports above it the main or operative parts of the engine. Said casing B is provided at its ends with top and bottom walls *b*, *b'*, and extends substantially an equal distance above and below 40 the flat top *a* of the stand A. As shown in the drawings, said stand A is made in two like parts or sections *a'*, *a''*, the meeting or opposing edges of which are provided with 45 semi-circular notches which register with each other to embrace the casing B when the sections of the stand A are assembled. The sections *a'*, *a''* are joined by bolts *a'*, *a''*, which serve to afford clamping engagement of the 50 said sections with the casing. (See Fig. 2).

C indicates a source of heat, in this instance, an alcohol lamp located within the casing B and seated on the bottom wall *b* thereof. An opening or doorway is made in

the cylindric wall of the said casing B below 55 the flat top *a* of the stand, so that the lamp C may be readily placed in, or removed from, the casing. The casing B constitutes the heating chamber of the engine.

D indicates a base member for the main 60 or operative parts of the engine, said base member having the form of a horizontal plate, which is supported above the heating chamber B by tubular spacing members *d* (four of which are shown in the drawings) 65 through which pass bolts *d'*, rigidly connecting the said base member D to the upper wall *b'* of said heating chamber. Secured to the under side of the base member D in line with an axially arranged opening therein and extending downwardly therefrom into the casing B through the top wall *b'* thereof, is the lower or heater part E of the expansion or displacer cylinder of the engine. Said lower or heater part E of the displacer cylinder is made of thin sheet metal. The lower end wall *e* of the heater part E of the said displacer cylinder is directly above and close to the lamp C. Secured to and projecting above the upper side of the base member 75 D, in line with the heater part E of the displacer cylinder, is the upper or cooler part F of the said cylinder, which is made of cast metal and closed at the top by a top wall *f*.

G, G, indicate laterally spaced, upwardly 80 extending brackets secured to the upper side of the base member D, by bolts *g*, *g*, at each side of the cooler part F of the displacer cylinder. Said brackets G, G are provided at their upper ends with bearings for a horizontally arranged crank-shaft H extending 85 between them and having rigidly secured to the outwardly extending ends thereof, outside of said bearings, fly-wheels J, J. Located within the displacer cylinder is a hollow displacer piston K of a diameter less than the inside diameter of the said displacer cylinder. Said displacer piston K is provided with an upwardly extending piston rod *k* rigidly connected to the upper end 90 thereof, and projecting through a stuffing box *k'* in the top wall *f* of the cooler part F of the said displacer cylinder. The upper end of the piston rod *k* is connected with a central crank pin *h*, on the crank-shaft H, 95 by a pitman *h'* whereby the said displacer piston K is reciprocated vertically within the displacer cylinder.

L, L indicate two upright working cylinders open at their upper ends and secured, at opposite sides of the cooler part F of the displacer cylinder, to the upper side of the 5 base member D, exterior to the brackets G, G. Located within the working cylinders L, L and adapted to reciprocate vertically therein, are snugly fitting working pistons l, l provided with connecting rods l', l', which are connected with the pistons by pivot pins l², l². The upper ends of said rods l', l' are connected with crank pins j, j on the outer faces of the fly wheel J, J. Ports or 10 passages M, M in the base member D afford communication between the lower or bottom ends of the working cylinders L, L and the upper end of the cooler part F of the displacer cylinder, so that air within the displacer cylinder may readily pass back and forth between the working cylinders and the displacer cylinder during the reciprocation of the pistons therein. The cooler part F of the displacer cylinder and the working cylinders L, L, are all cast together in one single 15 piece to gain cheapness of construction and accuracy in fitting. Laterally spaced grooved pulleys N, N are rigidly secured to the crank-shaft H inside of the brackets G, G and adapted to receive belts for the transmission of power.

The operation of the engine is as follows: The displacer piston K in the displacer cylinder being in its elevated position, namely, with its upper end practically 20 filling the cooler part F of said displacer cylinder, the pistons l, l, in the working cylinders L, L will be in their intermediate positions and moving upwardly. With the several pistons in the position above described, the main or principal part of the body of air in the displacer cylinder will be at the bottom of the same and between the bottom wall e of the heater part E of the displacer cylinder and the end of the piston K. The flame of the lamp C or other heating means acts directly on the end or bottom wall e of the heater part E of the said displacer cylinder and heats the said body of the air within the lower end thereof. As the said air is heated, it is caused 25 to expand and passes around the cylindrical wall of the loosely fitting displacer piston K, through the ports or passages M, M and into the working cylinders L, L, to act directly upon the working pistons l, l therein to effect their outward or upward strokes. Both of said pistons l, l move upwardly at the same time. This effects the 30 rotation of the fly-wheels J, J, and the crank shaft H, with the result that the displacer piston K in the displacer cylinder is made to move downward. When the pistons l, l are moving downwardly and are midway of their downward strokes, the displacer piston K is at the limit of its down-

ward stroke with its lower end practically filling the lower end or bottom of the heater part E of the displacer cylinder. (See Fig. 3). In this position of the piston K, its upper end is out of the cooler part F of the displacer cylinder, and the heated air previously in the lower part of the displacer cylinder will have passed into the space above the piston K. The walls of the cooler part F of the displacer cylinder being exposed to the atmosphere and removed from the source of heat, will be much cooler than the heater part E, and as the heated air contracts or is lessened in volume as it parts with its heat, a lessened pressure or partial vacuum will be produced in the upper part F of the displacer cylinder, and the air in the working cylinders L, L, below the pistons l, l, will pass into the displacer cylinder through the passages M, M. The pistons l, l moving downwardly through the power stored up in the fly-wheels, will tend to force the air beneath them through the passages M, M into the upper part F of the said displacer cylinder. According to the extent to which the cooling of the air in the top of the displacer cylinder tends to create a partial vacuum within the working cylinders L, L, the atmospheric pressure upon the exposed or upper ends of the pistons l, l, arising from such partial vacuum, will aid in drawing the said pistons downward. As the rotation of the fly-wheels J, J and the crank-shaft H, continues, and the reversal of movement of the pistons l, l is being effected at the lower limits of their strokes, the displacer piston K is drawn upwardly, or makes its upward stroke. As the displacer piston K moves upwardly, it displaces the contracted or cool air in the cooler part F of the displacer cylinder, and causes the said air to pass downwardly around the cylindrical wall of the said piston K into the lower end or bottom of the heater part E of the displacer cylinder, to be again heated and expanded, as before. It will be observed that the movement of the piston K displaces or shifts the principal part of the body of air within the displacer cylinder back and forth between the upper and lower ends of the same. Furthermore, the strokes of said displacer piston K are so timed, that it commences its upward and downward strokes when the working pistons l, l are midway of their upward and downward strokes and are exerting maximum turning effect on the crank-shaft, so that the air is being heated and expanded in the bottom of the displacer cylinder when the working pistons are exerting their greater effect on the crank-shaft in their upward movement, and the air in the top of the displacer cylinder is being cooled and contracted when the pistons are in position to exert the greatest 125 130 135 140 145 turning movement on the shaft in their downward strokes.

When the displacer piston is in its elevated position in the displacer cylinder, the body of the air in the lower part or bottom of the said cylinder, as it is heated and expanded, passes upwardly and also laterally or in a circumferential direction through the annular narrow space formed between the cylindrical wall of the displacer piston and the wall of the displacer cylinder to the ports or passages M, M, arranged at each side thereof, and diametrically opposite each other. The body of heated air divides as it rises through said annular space and an equal part thereof enters each of the working cylinders and acts on the pistons therein to effect their upward strokes, as above described. That part of the body of the heated air on the opposite sides of the displacer piston and at opposite sides of a vertical plane at right angles to a like plane passing through the passages leading to the working cylinders, need only travel a circumferential distance equal to one-fourth of the circumference of the said displacer cylinder or through an arc of 90 degrees, in order to gain access to the said ports or passages. This is made possible by the arrangement of the said working cylinders on each side of the displacer cylinder and diametrically opposite each other, as above described.

I am aware that hot air engines of the same general construction have been made, having one working cylinder in communication with one side only of the displacer cylinder. In such prior construction, that part of the body of heated air in the displacer cylinder at a point diametrically opposite the port or passage leading to the working cylinder, must travel a circumferential distance equal to one-half the circumference of the displacer piston, or through an arc of 180 degrees, in order to gain access to the said port or passage. By reason of the diametrical arrangement of the two working cylinders of the engine, illustrated, and of the passages M, M, by which the openings of said passages into the displacer cylinder are equally spaced circumferentially of the latter, I obtain uniform distribution of pressure to the two working cylinders, and avoid the frictional resistance or retardation of the flow of air from the bottom of the displacer cylinder to the working cylinders, such as occurs in such engines as heretofore constructed, wherein the air flowing upwardly through the annular space between the walls of the displacer cylinder and the displacer piston makes its exit from said annular space at one point only in the circumference of the displacer cylinder, and only a small part, if any, of the air in the part of said annular space opposite the single passage leading to

the working cylinder reaches the latter. It is to be noted that the free and rapid passage of the heated air to the working cylinders is of great importance in an engine of this kind because the engine must run at a very high rate of speed in order to develop any considerable amount of power. Careful tests with engines having a single working cylinder have demonstrated that the same are capable of producing a very small amount of power as compared with one having two working cylinders arranged as herein described, and that this is true regardless of the size of the diameter of the working cylinder or cylinders. In other words, it is found not to be possible to increase the power of the engine by merely increasing the size or diameter of a single working cylinder. This arises from the fact that the area of the working cylinder of a single cylinder engine must have a definite relation to that of the displacing cylinder, in order to give a maximum degree of power with a displacement cylinder of a given capacity, and no advantage is gained by increasing the size of such single working cylinder. When, however, two working cylinders are used, the combined piston areas thereof may be made materially greater than the piston area of a single cylinder, with corresponding advantage in the amount of power developed; it being understood that the effective action of two cylinders is obtained by so arranging the same and the passages connecting them with the displacement cylinder, that said passages open at equally spaced points circumferentially into the displacer cylinder, so as to facilitate and make uniform the passage of air to and from the working cylinders, as hereinbefore stated. The comparative inefficiency of a single cylinder engine is also largely due to the fact that with a single working cylinder the passage leading to such cylinder must be made comparatively large, and the air will pass through such large passage so freely that the working cylinder will become unduly heated, the air entering the displacer cylinder from the working cylinder will not be materially cooled, and the cooling effect in the top of the displacer cylinder will not be sufficient to counteract the effect of the large body of heated air delivered thereto from the working cylinder. By using two cylinders, the passage to each may be made of the proper size to insure a substantial cooling of the heated air before it passes from the working cylinders back to the top of the displacer cylinder; it being understood that a certain degree of cooling of the air in its passage to and from the working cylinders, as well as the cooling of the air in the top of the displacer cylinder, is a factor in obtaining effective operation of the engine. The opposite arrangement of the two working cylinders also affords the ad-

vantage that the piston of both cylinders may act on crank pins located at opposite ends of a single crank shaft.

An engine embracing the general features set forth may be variously constructed in its details, and I do not desire to be limited to the specific features shown, except so far as pointed out in the appended claims.

I claim as my invention:

- 10 1. In a hot air engine, a single displacer cylinder, a one-part displacer piston therein, a plurality of upright working cylinders having working pistons therein, said working cylinders being parallel to each other
- 15 and to said single displacer cylinder, each working cylinder being provided with a port or passage opening into the same displacer cylinder at points equally spaced circumferentially of said displacer cylinder, and a
- 20 horizontally arranged crank-shaft supported above said cylinders having a central crank pin for the displacer piston, the same crank-shaft being provided with a plurality of crank pins for the working pistons, said
- 25 displacer piston being provided with a piston rod connected with said central crank pin and each of said working pistons being provided with a piston rod connected with one of the crank pins provided therefor; the crank pins
- 30 with which the working pistons are connected being so arranged with respect to the displacer piston crank pin, that said working pistons move simultaneously in the same direction, and when in their midway position,
- 35 the displacer piston is either at the limit of its outward or inward stroke.
2. In a hot air engine, a single displacer cylinder, a one-part displacer piston therein, two upright working cylinders having working pistons therein, said working cylinders being parallel to each other and to said single displacer cylinder and arranged at opposite sides of said single displacer cylinder, each of said working cylinders being pro-
- 40 vided with a port or passage opening into the same displacer cylinder at the upper part thereof and at points diametrically opposite each other, and a horizontal crank-shaft supported above said cylinders having
- 45 a central crank pin, the same crank-shaft having a crank pin at each end thereof, said displacer piston being provided with a pis-

ton rod connected with said central crank pin and each of said working pistons being provided with a piston rod connected with one of the crank pins at the ends of the crank-shaft; the crank pins at the ends of the crank-shaft being so arranged with respect to the central crank pin that said working pistons move simultaneously and when in their midway position and moving outward, the displacer piston is at the limit of its outward stroke and when said working pistons are in their midway position and moving inward, said displacer piston is at the limit of its inward stroke.

3. In a hot air engine, an upright casing forming a lamp chamber, a support for said casing, a horizontally arranged base member for the operative parts of the engine supported above said upright casing, a single displacer cylinder comprising a heater part and a cooler part, the former being secured to and extending from said base member into said upright casing, and the latter being secured to and projecting above the said base member, a displacer piston in said displacer cylinder, two upright working cylinders having working pistons therein mounted on said base member at opposite sides of the displacer cylinder and being parallel to each other and to said displacer cylinder, each of said working cylinders being provided with a port or passage opening into the cooler part of the same displacer cylinder at points diametrically opposite each other, upright brackets mounted on said base member, and a horizontally arranged crank-shaft mounted in said brackets, said crank-shaft being provided with a central crank pin and a crank pin at each end thereof, said displacer piston being provided with a piston rod connected with said central crank pin and each of said working pistons being provided with a piston rod connected with one of the crank pins at the ends of said crank-shaft.

In testimony, that I, claim the foregoing as my invention I affix my signature in the presence of two witnesses, this 23d day of March A. D. 1912.

JACOB R. SANDAGE.
